ENGINE-STARTING DEVICE.

1,244,004.

Specification of Letters Patent.

Patented Oct. 23, 1917.

Application filed November 11, 1916. Serial No. 130,797.

To all whom it may concern:

Be it known that I, EDWARD J. TOMLINSON, a citizen of the United States, a resident of Newark, in the county of Essex and State 5 of New Jersey, have invented certain new and useful Improvements in Engine-Starting Devices, of which the following is a specification.

My invention relates to starting devices 10 for engines such as internal combustion engines commonly used in the propulsion of automobiles and similar autovehicles.

The present invention has as one of its 15 objects to provide a starter in which the novel arrangement and coöperation of the various elements contribute to give a thoroughly dependable and automatic device.

Another object is the provision of a device 20 of this character wherein an electric motor, through the agency of a driving member, is adapted to engage and positively drive a member operatively connected to the engine, and in accordance with this provision I have so designed my starter that 25 the driving force is distributed and shared by members capable of resisting the stresses set up while the engine is being cranked. By thus employing a positive drive the use 30 of all flexible and resilient means such as springs has been avoided.

Still another object is to secure a self contained and compact device, to be easily mounted in working relation with the engine, one in which a well balanced system 35 of working elements is adapted to be enclosed and protected against the liability of injury or interference in operation. These and other objects will be better understood from a consideration of the following 40 description taken in conjunction with the accompanying drawings, wherein like characters of reference designate like parts in each of the respective views.

Figure 1 is a longitudinal elevation, partly 45 in section, showing a portion of the electric motor used in the present embodiment, and further illustrating the arrangement of the various elements associated with the driving member. In this view the driving member 50 is seen to be in its normal inoperative position.

Fig. 2 is a view similar to Fig. 1 with the exception that the driving member is shown 55 in operative engagement with the engine fly wheel.

With particular reference to the drawings, 1 is the armature of the driving motor having a plain shaft extension 2. It will be noted at this point that while I make use of an electric motor, I am well aware 60 that any other suitable source of power may be used instead, and while the shaft 2 is by preference a continuation of the armature shaft, yet it is obvious that other arrangements may be employed, such as a counter 65 shaft having a suitable driving connection with said motor armature. The frame 3 serves as a casing for the motor, and being continued at one end of said motor it further provides an inclosure within which is 70 contained substantially the entire driving mechanism. An end plate 4 is adapted to fit on the end of frame 3, being secured in place by suitable means as by bolts, one of which is shown at 5. Mounted upon the 75 shaft 2 at a point adjacent armature 1 is a spider or yoke 6, having arms 7 and 8 projecting radially from said shaft. Spider 6 is secured to shaft 2 to rotate therewith by means of a key 9. A pin 10 passes through 80 the hub of spider 6 and through shaft 2 to assist in holding spider 6 rigidly upon said shaft, and to prevent the tendency of any creeping motion. Fastened to spider 6, in a manner which will presently be described, 85

are shaft members 11 and 12. These members as seen are in the nature of bolts, having formed integrally therewith heads 13 and 14 respectively. At the other end members 11 and 12 have their diameter diminished to give the reduced portions 15 and 16. Said reduced portions of members 11 and 12 are adapted to pass through corresponding bores in the radial arms 7 and 8 respectively of the spider 6. The abrupt 90 shoulders formed by the reduction in diameter of members 11 and 12 bear respectively against the faces of radial arms 7 and 8 to hold said members against longitudinal displacement. Nuts 17 and 18 are then applied to the threaded ends of said members and set up against the opposite faces of said arms, whereby said shaft members 11 and 12 are secured firmly in position.

Previous to the assembly just described, 105 hollow sleeves 19 and 20 are passed upon shafts 11 and 12, being of such internal diameter as to be permitted of free rotary movement upon said shafts as bearings, and being of sufficient length to allow the end- 110

play, between heads 13, 14 and radial arms 7, 8 respectively, necessary to the rotary movement for which said sleeves are adapted. The external surfaces of sleeves 19 and 20 are provided with spiral gear teeth 21 and 22, the function of which will hereinafter be described. Upon sleeves 19 and 20 and at the ends thereof remote from the spider 6 there are mounted spur toothed pinions 23 and 24. Said pinions are of like diameters, each having the same number of teeth, and are suitably fastened upon the corresponding sleeves as by keys, one of which is shown at 25, whereby sleeves 19 and 20 are constrained to participate in the rotation of pinions 23 and 24 respectively. In the central portion of end plate 4 is a boss 26 with a circular recess passing therethrough and adapted to align with the axis of shaft 2. 27 is a hollow spur gear member having a hollow sleeve 28, which sleeve is adapted to fit into the said recess in end plate 4. A key 29 coöperates with keyways in both sleeve 28 and boss 26 to hold the pinion 27 stationary. A threaded washer 30 engages the threaded end of sleeve 28 and seats up against the boss 26, and thereby prevents any danger of said pinion working loose. When so assembled and secured in position 30 pinion 27 is in meshing engagement with pinions 23 and 24, whereby when said pinions are revolved with spider 6 about the axis of shaft 2 as a center, they also receive an axial rotation by virtue of their tooth engagement with stationary pinion 27.

Coming now to the description of the driving member, there is seen to be a hollow pinion 31 having an integrally formed hollow sleeve 32 projecting laterally from the inner face thereof. Said hollow pinion and sleeve provide a circular recess which extends through the entire length of the driving member, and is of such diameter that said driving member is adapted to fit 40 upon the shaft 2 for a sliding longitudinal motion with respect thereto. The hollow recess in pinion 27, previously referred to, is of a size necessary to accommodate sleeve 32 for both axial and rotary movements. 50 Secured fast to the inner end of sleeve 32 by some suitable means such as a shrink fit and a key 33 or an alternative arrangement such as a key, taper and nut on the end of said sleeve is a gear member 34. Said gear 55 34 is adapted to mesh with both of the spirally toothed sleeves 19 and 20, and accordingly has its surface provided with spiral teeth to correspond with the teeth on said sleeves. Disposed about shaft 2 and preferably adjacent spider 6 is a resilient means 60 in the form of a coiled spring, whose function it is to absorb the shock as the driving pinion 31 is thrown to its home position subsequent to the starting of the engine. Said 65 spring is of such resiliency and is so propor-

tional relative to the travel of the driving pinion 31 that the total impulse of said pinion, while being thrown to its off position, is absorbed to thus prevent the face 36 of said pinion from striking severely against the washer 30. At 37 I have shown a portion of the engine fly wheel having teeth thereon which is adapted to be engaged and driven by pinion 31. However, it will be understood that said pinion may engage any 75 suitable member operated by the engine without deviating from the intended purpose.

Considering the operation of my improved starter and assuming the engine to be at 80 rest, and the driving member of the starter in its inoperative position, as shown in Fig. 1, suppose it is desired to start the engine. A suitable source of power such as a storage battery (not shown) is applied to the 85 motor armature 1. As said armature and its shaft 2 begin to rotate, the spider 6, being fastened to said shaft, rotates in unison therewith. Consequent to such rotation the shafts 11 and 12 with their corresponding 90 sleeves 19 and 20 and tooth pinions 23 and 24 all revolve in a circular path about the center of shaft 2 as an axis. Since the gears 23 and 24 are in continual mesh with stationary gear 27, and since the sleeves 19 and 95 20 are loosely mounted upon shafts 11 and 12 respectively, to which sleeves gears 23 and 24 are correspondingly fastened, it will be evident that as the several elements revolve about the axis of shaft 2 pinions 23 100 and 24 together with sleeves 19 and 20 will further be required to rotate upon their respective shafts 11 and 12. In the meantime the sleeves 19 and 20 being in spiral tooth engagement with pinion 34 of the driving 105 member, a thrusting force is imparted to said pinion which moves the pinion 34, sleeve 32 and pinion 31, comprising the driving member, axially along the shaft 2. While driving pinion 31 is thus being advanced it 110 also receives a rotary motion, due to the action of said spiral thread engagement, which serves to insure a proper meshing of said pinion 31 with the gear teeth on engine wheel 37. Pinion 31 continues to advance 115 along shaft 2 until it has reached its position of complete mesh with the fly wheel. At this point the outer lateral face of gear 34 has come in contact with stationary gear 27, and being prohibited from further axial motion said gear is driven by sleeves 19 and 20 to drive pinion 31 and thereby the engine wheel 37. When the engine has performed the necessary number of cycles to start of its own accord the engine member 37 will 120 rapidly accelerate and acquire a velocity greater than that at which it was driven by pinion 31 while the engine was being cranked. The engine is now tending to drive the pinion 31 and consequently the thrust- 125 130

ing action between pinion 34 and sleeves 19 and 20 is reversed which results in withdrawing the driving pinion 31 from engagement with fly wheel 37. As the engine is apt to 5 pick up very rapidly the driving member is thrown to its home position with considerable impulse. To eliminate any danger of injury to the starter, buffer member 35 is designed to receive the impulse of said throw 10 and thereby absorb the shock attendant to the disengagement from the engine member.

It will be observed that in my starter I have employed the so-called sun and planetary system of gears in which pinions 23 and 24 are adapted to revolve about gear 27. By this arrangement the pinions 23 and 24 furnish the rotation of sleeves 19 and 20 necessary to advance pinion 31 into engagement with the engine, and also the driving 20 force necessary to the cranking of said engine. While the spider 6 is shown to have but two arms each fitted with a spiral and spur toothed member as described, it will be understood that, if desirable, any suitable 25 number of such elements may be carried by said spider. By a proper proportioning of the various gear members in my starter any desirable mechanical advantage may be given the motor.

30 While I have shown but one embodiment of my invention, which typifies a starter of the outboard bearing class or one in which the starter pinion draws away from its bearing, it is evident that by a suitable 35 arrangement of gears the reverse operation may be secured. Neither do I care to limit myself to the exact details shown as it is apparent to those skilled in the art that many changes and alterations may be made 40 without departing from the spirit of the present invention and scope of the appended claims.

Having thus described my invention what is claimed is:-

45 1. In an engine starting device including in combination with a member operated by the engine, an electric motor having an armature shaft projection, a driving member mounted upon and actuated by said shaft projection for the purpose of driving said engine member, a power transmitting member mounted upon said driving member, gear wheels spaced from and adapted to revolve with said motor shaft and coacting 50 with the said power transmitting member to move the driving member into driving engagement with said engine member.

2. In an engine starting device including in combination with a member operated by 60 the engine, an electric motor having a shaft projection, a driving member mounted upon said shaft and adapted to move axially with respect thereto, a power transmitting member mounted upon said driving member, gear wheels spaced from and adapted to re-

volve with said shaft and coacting with the said power transmitting member to move said driving member into driving engagement with the engine member and also to furnish a driving connection between the 70 driving member and said shaft projection.

3. In an engine starting device including in combination with a member operated by the engine, a motor having a shaft projection, a driving member mounted upon and 75 adapted to move axially with respect to said shaft projection, a power transmitting member mounted upon said driving member, gear wheels spaced from and adapted to revolve with said shaft projection and coacting 80 with the said power transmitting member to automatically move said driving member into and out of driving engagement with the engine member.

4. In an engine starting device including 85 in combination with a member operated by the engine, a motor having an armature shaft projection, a driving member mounted upon and adapted to move axially with respect to said shaft projection, a power 90 transmitting member mounted upon said driving member, spiral gear wheels spaced from and adapted to revolve with said shaft projection and coacting with the said power transmitting member to automatically engage 95 and disengage said driving member with the engine member and also to furnish a driving connection between the driving member and said shaft projection.

5. In an engine starting device including 100 in combination with an engine operated member, a motor driven shaft, a driving member driven thereby for the purpose of driving said engine member, gear members spaced from and supported by said shaft 105 and adapted to revolve therewith, said driving member having a gear member meshing with each of the first gear members, whereby when said shaft operates said first mentioned gear members revolve in a path about 110 said driving member gear to move said driving member into operative engagement with the engine member.

6. In an engine starting device including in combination with the engine flywheel, a 115 motor driven shaft, a driving member mounted upon said shaft and having a gear wheel thereon, a spider secured to said shaft, gear members supported by said spider in mesh with said gear wheel and adapted to 120 revolve in a path about said gear wheel when the motor shaft is rotated, whereby said driving member is moved into and out of driving engagement with the engine flywheel, and means to absorb the impulse of 125 the driving member when the same is disengaged from said flywheel.

7. In an engine starting device including in combination with a member connected to the engine, a motor driven shaft, a driving 130

member having a gear wheel and being mounted upon said shaft for longitudinal movement relative thereto, a spider fixed to said shaft and having stub shaft members thereon, gear members mounted upon these 5 stub shaft members and coöperating with said gear wheel of the driving member in such a way that when said motor shaft rotates said driving member is automatically advanced into driving engagement with the engine member.

8. In an engine starting device including in combination with an engine operated member, a motor driven shaft, a spider fixed 10 upon said shaft for rotation therewith, stub shaft members securely fastened to the arms of said spider, toothed sleeves rotatably mounted on said shaft members, pinions securely mounted upon said toothed sleeves, a 15 stationary gear supported by the motor frame and meshing with said pinions, a driving member mounted upon said motor shaft and having a gear wheel adapted to mesh with said toothed sleeves, whereby 20 when said motor shaft is rotated said toothed sleeves are actuated to move said driving member into driving engagement with the engine member.

9. In an engine starting device including 25 in combination with an engine operated member, a motor driven member adapted to engage and drive said engine member, means including a stationary gear for causing said motor driven member to engage with the 30 engine member, said stationary gear serving also as a bearing for said motor driven member.

10. In an engine starting device including in combination with an engine driven member, a motor driven member adapted to engage and drive said engine member, means including a gear member for causing said motor driven member to engage with the engine member, said gear member serving also 40 as a bearing in which said driving member is adapted to slide while passing into said engagement with the engine member.

11. In an engine starting device including in combination with an engine operated member, a motor driven shaft, a driving member driven by said shaft and adapted to engage and drive said engine member, means including a stationary gear for moving said driving member to engage said engine member, said stationary gear also serving as a bearing for the driving member and the driving member serving as a journal for said shaft.

12. In an engine starting device including 60 in combination with an engine operated member, a motor driven shaft, a driving member driven thereby and adapted to engage and drive said engine member, means coöperating with the rotation of said shaft 65 and including a gear member to automati-

cally move said driving member into engagement with the engine member, said gear member serving also as a bearing in which said driving member is adapted to operate as a sliding journal for said motor driven 70 shaft.

13. In an engine starting device including in combination with a member operated by the engine, a motor, a shaft driven thereby, a supporting member secured to and adapted 75 to rotate with said shaft, a stationary gear supported by the motor frame, a driving member mounted upon said shaft for longitudinal movement relative thereto, means carried by said supporting member and co- 80 operating with said stationary gear and driving member whereby said driving member is moved into and out of driving engagement with the engine member, and a resilient member to receive the impulse of said driving 85 member when thrown from said engagement with the engine member.

14. In an engine starting device including in combination with a member operated by the engine, a motor, a shaft driven thereby, a supporting member secured to and adapted 90 to rotate with said shaft, a stationary gear supported by the motor frame, a driving member mounted upon said shaft for longitudinal movement relative thereto, means carried by said supporting member and co- 95 operating with said stationary gear and driving member whereby said driving member is moved into and out of driving engagement with the engine member.

15. In an engine starting device including in combination with a member operated by the engine, a motor driven shaft, a supporting member secured to and adapted to rotate with said shaft, power transmitting members 105 rotatably mounted upon said supporting member, a housing for said supporting and power transmitting members, a driving member having a gear within said housing and a gear exterior of said housing, a stationary 110 gear supported by said housing, said power transmitting members coöperating with said stationary gear and also with the gear of said driving member within said housing to move said exterior gear of the driving member into driving engagement with the engine member.

16. In an engine starting device including in combination with a member operated by the engine, a motor driven shaft, a driving member mounted thereupon for axial movement relative thereto, means including a stationary gear for causing said driving member to move into operative engagement with said engine member, said stationary gear 120 serving as a bearing for said motor driven shaft and also as a stop for the axial movement of said driving member.

17. In an engine starting device including in combination with the engine fly wheel, 130

an electric motor having an extended armature shaft, a driving member mounted upon said shaft and adapted to move axially with respect thereto into and out of driving engagement with said fly wheel, a spider mounted upon and adapted to rotate with said shaft, spiral gear members carried by said spider, spur gear members carried by said spider, a spiral gear carried by said driving member, a spur gear rigidly fixed to

the frame of said motor, the spiral gear members of said spider coöperating with the spiral gear of said driving member, and the spur gear members on said spider coöperating with said rigidly fixed gear to move said 15 driving member into engagement with the engine fly wheel.

In witness whereof I affix my signature.

EDWARD J. TOMLINSON.
